[57] CLAIM

The ornamental design for an electronic thermometer case, as shown.

DESCRIPTION

FIG. 1 is a top and left front perspective view of an electronic thermometer case showing my new design; FIG. 2 is a top plan view thereof; FIG. 3 is a left side elevational view thereof with a portion broken-away for ease of illustration of the probe well;

FIG. 4 is a front elevational view thereof;

FIG. 5 is a rear elevational view thereof;

FIG. 6 is a right side elevational view thereof; and

FIG. 7 is a bottom plan view thereof.

The broken-line showings of probes and cables in FIGS. 1-7 are environmental only and form no part of the claimed design.
